UNITED STATES PATENT OFFICE.

GUSTAVE A. ZAPF, OF NEW YORK, N. Y.

INHALING SYSTEM.

1,129,619.

Specification of Letters Patent. Patented Feb. 23, 1915.

Application filed July 10, 1914. Serial No. 850,069.

To all whom it may concern:

Be it known that I, GUSTAVE A. ZAPF, a citizen of Austria, residing in New York city, county of New York, State of New York, have invented a new and useful Improvement in Inhaling Systems, of which the following is a specification.

This invention relates to a device of novel construction for supplying patients in hospitals and other persons with fresh breathing air which is heated or cooled as circumstances may require in order to have the desired effect.

In the accompanying drawing which is a diagrammatic elevation of an inhaling system embodying my invention, the numeral 1 indicates a heating or cooling chest containing a pipe coil 2 that communicates through inlet pipe 3 with the atmospheric air, the drawing showing said pipe passing from the interior of a room through a window pane 4 into the open air. Coil 2 is further connected through pipe 5 with an air distributing chamber 6 which is provided with a thermometer 7. Chamber 6 is furnished with a plurality of nipples 8 by means of which connections may be made between said chamber and a number of different rooms, floors or apartments, said nipples being adapted to be coupled to air supply pipes 9. Each pipe 9 extends along the floor 10 of a room and is here provided with a plurality of nipples 11, with which the inlet ports of the several inhaling appliances 12 may be connected by flexible tubes 13. For collecting the exhaled foul air and discharging the same into the open air, an air outlet pipe 14 is provided. The latter is furnished with a plurality of nipples 15 to which exhaust pipes 16 extending along the ceilings of the various rooms may be connected. Each exhaust pipe 16 is in turn provided with nipples 17 to which the outlet ports of the inhaling appliances may be connected by flexible tubes 18. The outlet pipe 14 is of a larger diameter than the air intake pipe 3 and extends vertically beyond the same so as to induce a natural draft within the several conduits of the inhaling system for removing the foul air therefrom.

If cool air is required for breathing purposes, cold air may be admitted into chest

1 through a pipe 19, or ice may be packed around coil 2. If on the other hand, hot air is required, steam or another heating medium is admitted into the chest through a pipe 20.

The inhaling appliances proper may be of any suitable construction. Thus for instance, the head of a patient lying in bed 60 may be inserted into the lower padded half of a box 21 whereupon the windowed cover 22 is closed, a rubber packing fitted around the patient's neck providing a substantially air tight closure. Instead of this box, a mask 65 23 covering the mouth and nose of a person who has to work in a poisonous or other unhealthy atmosphere may be used.

It will be seen that by the construction described breathing air which is heated or 70 cooled to the extent desired, may be passed through any number of appliances by means of which it is applied to patients or workmen operating in foul air. Although the drawing shows my improved inhaling system in conjunction with inhaling appliances for human beings, it is obvious that also similar appliances for supplying breathing air to animals may be connected to said system without departing from the spirit of 80 my invention.

I claim:

An inhaling device comprising an air inlet pipe, a temperature regulating device communicating therewith, an air distributing 85 chamber communicating with the temperature regulating device, an air supply pipe communicating with the distributing chamber and extending along the floor of a room, an air outlet pipe extending along the ceiling of said room, flexible tubes connected to the air supply pipe, additional flexible tubes connected to the air outlet pipe, inhaling appliances interposed between the first named tubes and the last named tubes, and 90 an upright air discharge pipe communicating with the air outlet pipe, said air discharge pipe extending a distance above the air inlet pipe.

GUSTAVE A. ZAPF.
